UNITED STATES PATENT OFFICE.

BEULAH H. DRYER, OF ROCHESTER, NEW YORK, ASSIGNOR OF ONE-HALF TO GERALD H. DRYER, OF ROCHESTER, NEW YORK.

REVERSIBLE DRESS.

Application filed February 25, 1926. Serial No. 80,673.

The object of this invention is to provide a new and improved form of reversible dress.

This and other objects of the invention 5 will be fully illustrated in the drawings, described in the specification and pointed out in the claims at the end thereof.

In the drawings:

Figure 1 is a front elevation of the dress.

10 Figure 2 is a vertical perspective view of the left hand portion of the dress, the right hand portion being cut away.

Figure 3 is a plan view of one half of the dress either front or back.

15 Figure 4 is a section through the cuff on the line 4^x, 4^x of Figure 1.

Figure 5 is a section through the collar on the line 5^x, 5^x of Figure 2.

20 In the drawings like reference numerals indicate like parts.

In the drawings reference numeral 1 indicates the front of the dress and 2 indicates the back of the dress. The front and back of the dress are each made of one 25 piece of cloth cut to the outline shown in Figure 3. These two pieces are joined together along the side seams 3, 4 and along the shoulder seams 5, and 6. Each half of the dress is provided with a pocket 7,

30 8 as shown in Figure 2. As the dress appears in Figure 2 the pocket 7 is on the outside of the dress at the front and the pocket 8 is on the inside of the dress at the back. When the front and back of the 35 dress are joined together armholes are provided at 9 and 10 and these are finished with the cuffs 11 and 12. The dress is also provided with a V shaped neck opening 13 which is finished with a V shaped collar

40 14. The collar 14 is in two pieces right and left, one on each side of the neck and each piece of the collar is made of two pieces suitably joined together at the curved outer edge and joined to the body of the 45 dress along the neck line. Each cuff is made of one straight piece doubled on itself and joined to the body of the dress around the armholes. The dress is also provided with a belt 15, the loose ends of which are tied

50 together at either the front or back of the dress. It is also provided with belt slips on the inside and out to support the belt.

The dress so made has a seam on each of the shoulders and down each side of the 55 dress, and it has a V shaped neck line both

front and back with a reversible collar split at the bottom of the V both front and back. The cuffs are one piece cuffs and are reversible. It is provided with a hem at the bottom of the dress which is the only hem 60 in the dress. It is a slip-on dress and therefore buttons and button holes therein are not needed.

The dress is reversible from inside back to the outside front and presents the same 65 appearance in either position and also can be turned around from front to back.

In the ordinary wash dress when the front of the dress becomes soiled, it is necessary to have the dress washed before it can be 70 worn again. It is a well known fact that the outside back of the dress can become soiled almost as quickly as the outside front of the dress. If the front becomes soiled the dress can be turned half way around so that 75 the soiled front is at the back and the soiled back is at the front. Such an expedient, however, does not help much in prolonging the wear of the dress between washings, especially in dresses for children. But the 80 inside of the dress both front and back will remain clean after the outside has become soiled, and by turning the dress inside out, and then by turning it half way around, the original inside back of the dress 85 becomes the outside front of the dress. I have made my dress that is shown in this application so that it can be used in both positions and will present the same clean appearance in either position, and because 90 the inside of the dress has been kept clean while it was the inside when it is turned inside out and turned half way around, the dress is given a clean and neat appearance in its new position. Therefore, the dress can be 95 worn in both positions as a clean dress for each washing. It will also be understood that the dress can be turned halfway around without being turned inside out so that it is possible to wear the dress in either of 100 four positions.

The collar and cuffs are reversible so that they will look the same in either position and flat or felled seams are used so that they look the same on either side.

I claim:

1. A dress composed of two similar sections joined along the sides and shoulders to form the front and rear of the dress, the front of the front section being provided 110

with certain embellishments to improve its appearance and utility, the front of the rear section being provided with similar embellishments, whereby the front of the rear is converted into a substantial duplicate of the front of the front, each of said sections being provided with a V shaped notch to form a neck opening, said notch having the same appearance in both the front section and rear section, and a collar stitched to the edges of said neck opening and adapted to hinge around said edges, said collar having the same appearance on each face thereof, all of said elements cooperating to permit said dress to be worn with either side out and to present the same appearance when turned inside out and half way around.

5. A dress as defined in claim 1, certain of said embellishments consisting of loops to provide for the passage of a belt there-through.

10. In testimony whereof I affix my signature.

BEULAH H. DRYER
